UNITED STATES PATENT OFFICE.

WILLIAM C. LAUTNER, OF DETROIT, MICHIGAN.

DESIGN FOR A BASE FOR BURIAL-CASKETS.

SPECIFICATION forming part of Design No. 26,907, dated April 13, 1897.

Application filed April 13, 1896. Serial No. 587,413. Term of patent 14 years.

To all whom it may concern:

Be it known that I, WILLIAM C. LAUTNER, a citizen of the United States, residing at Detroit, county of Wayne, State of Michigan, 5 have invented and produced a new and original Design for Burial-Caskets, of which the following is a full, clear, and exact description, reference being had to the accompanying drawing, which forms a part of this specification.

The drawing is a view in perspective, showing my design.

The leading feature of my design consists in the design for the base of a burial-casket, 15 embodying a head having a raised outline, both the front and rear portions of the base having their upper edges lowered toward the foot from the raised head portion, the raised outline or head portion forming shoulders between the topmost edge thereof and the upper edges of the lowered front and rear portion of the base.

In the drawing, A is the base, having a head A' of raised outline, the body or shell 25 thereof toward the foot from said head carried upward at the front and rear of desired width from the bottom thereof, the front and rear of the body toward the foot from said head being of substantially the same width 30 or height, the foot of the casket being level with the front and rear sides adjacent thereto.

A shoulder α is shown in the general outline at the head of the casket, between the topmost edge thereof and the upper edge of the base toward the foot. The upper edges 35 of both the front and rear portions of the shell of the base extend toward the foot from said shoulder on substantially a straight line.

A bead or molding A' is located at the upper edge of the shell of the base, as shown, although the said bead or molding is not an essential feature of my design.

The shell of the base of the casket is upholstered substantially to a level with the upper front and rear edges of the shell at the head and the foot thereof, giving to the casket-base the general appearance of a couch with a raised head portion and a substantially horizontal body portion extending to 50 the foot from said raised head portion.

What I claim is—

The design for the base of a burial-casket, substantially as herein shown and described.

In testimony whereof I sign this specification in the presence of two witnesses.

WILLIAM C. LAUTNER.
